UNITED STATES PATENT OFFICE.

OWEN L. RIMEL, OF HARRISBURG, PENNSYLVANIA.

KNITTING MACHINE.

Application filed February 20, 1926. Serial No. 89,656.

This invention provides a reversible plating attachment for circular-knitting machines for manufacture of figured hosiery, and it is adapted for use on machines for 5 production of hosiery having seamless leg portions.

The attachment pertains to control of the yarn supplied to the needles, and it so is arranged that at proper and predetermined 10 times yarn-shifting and tension instrumentalities automatically are operated by a controlling part of the machine—as the pattern-chain, for example—to alter the supply of yarn of different colors or other characteristics.

More particularly, the attachment operates to shift yarn fingers and alter yarn tension, whereby yarn of one characteristic periodically is caused to be knitted differently with respect to other yarn entering 20 into the product, as, for example, when a colored yarn and a white yarn are thrown into or out of position with respect to the needles and knitted on the outside or inside 25 of the fabric.

When considered with the description herein, the characteristics of the invention are apparent from the accompanying drawings, forming part hereof, wherein an embodiment of the invention is disclosed, for 30 purposes of illustration.

Although the disclosures herein exemplify what now is considered to be a preferable embodiment of the invention, it is to be 35 understood that it is not the intention to be limited necessarily thereto in interpretation of the claims, as modifications and adaptations within the limits of the claims can be made without departing from the nature 40 of the invention.

Like reference-characters refer to corresponding parts in the views of the drawings, of which—

Fig. 1 is a front elevation of a knitting- 45 machine having the attachment associated therewith, such parts of the machine as do not relate directly to the functioning of the attachment being omitted or not referred to herein;

Fig. 2 is a side elevation of the machine, 50 with certain parts in section;

Fig. 3 is a plan view of the attachment and certain associated parts of the machine;

Fig. 4 is a front elevation of the attachment;

Fig. 5 is a side elevation thereof;

Fig. 6 is a view of the other side thereof. Having more particular reference to the drawings, A designates a part at the top of the machine above the needles thereof, to 60 which a supporting or base element of the attachment is secured by fasteners 8. This element includes an upright metallic plate 9, having an opening 10 in its lower portion, and it is formed integrally at its top with 65 a rearwardly-extending arm 11 and a forwardly-extending arm 12. The frame also includes a substantially U-shaped part comprising rearwardly-extending arms 13 secured to the rear side of the plate below 70 the arm 11.

By means of a screw or other suitable fastener 14 a transverse substantially horizontal shaft 15 is secured intermediately of its ends to the arm 12 at or near its free end. 75 The shaft has an abutment 16 on each side of the arm 12 and threaded end portions 17. A pair of yarn-tension members 18 of disk form, each having a notch 19 in its periphery, is held against each of the abutments 80 16 by a spring 20 on the shaft, which is interposed between the members 18 and nuts 21 on the threaded portions of the shaft.

A standard 22 is secured in any suitable manner to the upper side of the arm 12, 85 as by the fastener 14, which holds the shaft 15. The standard has at its upper end an integrally-formed transverse part 23, which carries guides 24 arranged to direct yarn between the pairs of disks 18. A rod or the 90 like 25, secured to the standard at or near its base, extends laterally therefrom and seats in the notches 19 of the disks, whereby the latter are prevented from turning under the influence of yarn passing therebetween. If 95 desired, the standard may be made of bendable sheet metal, so that the positions of the guides with respect to the disks may be adjusted.

A rock-shaft 26 is journaled in and carried by the frame members 13. By means of a set-screw 27 a collar 28 adjustably is secured to the shaft 26. An arm 29, which may be of stout wire, is mounted on and extends forwardly from the collar to a place 100 above one pair of the disks 18, and it has a pointed end portion 30 arranged to be moved between and thus separate the disks of that pair. Similarly by means of a set-screw 31 a collar 32 adjustably is secured 105 to the shaft 26. An arm 33, similar to arm 29, is mounted on and extends forwardly 110

from the collar 32 to a place below the other pair of disks 18, and it has a pointed end portion 34 arranged to be moved between and thus separate the disks of that pair. 5 The arms 29 and 33 relatively are arranged in such manner that, when the end of one of them is between the disks of its pair, the other is free of its pair, and on rocking of the shaft 26 one arm is moved between its disks and the yarn therebetween thus relieved of tension thereof and the other arm is released from its disks and permits them 0 to apply tension to its yarn.

The shaft 26 carries, and has secured thereto by a set-screw 35, a collar 36, which has a depending arm 37; and it also carries, and has secured thereto by a set-screw 38, a collar 39, which includes a cam or other eccentric part 40. The cam acts against an arm 41 swingably depending from the rearwardly-extending arm 11 of the frame. The arms 37 and 41 bear against ends of yarn-fingers 42 and 43, respectively, which are held against the arms by springs 44, and which extend into the machine to places to control the positions of yarn passing therethrough to the needles. Yarn passing between the pair of tension-disks controlled by the arm 29 passes through the yarn-finger 42 controlled by the arm 37, and yarn passing between the other pair of tension-disks controlled by the arm 33 passes through the yarn-finger 43 controlled by arm 41.

The movable elements of the attachment 35 so are coordinated that, when the tension-control arms 29 and 33 are engaged with and disengaged from their respective tension-disks, the depending arm 37 is retracted and permits the yarn-finger 42 to be in retracted position, and the cam 40 holds the arm 41 and the yarn-finger 43 in forward position, as shown by Fig. 6. When the 40 shaft 26 is rocked in the proper direction, the arm 37 moves the yarn-finger 42 forwardly, the arm 29 is released from the tension-disks between which yarn passes to that finger, the cam 40 turns and permits the arm 41 and the yarn-finger 43 to retract under the influence of a spring 44, and arm 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850

65 The shaft 26 may be rocked, in any suit-

able manner, in consonance with the functioning of other parts of the machine, to change periodically the pattern of the fabric being produced. For example, that shaft may have a crank 45, to which is connected 70 a spring 46. That spring holds the crank in contact with a substantially horizontal end portion 47 of a vertically-movable rod 48, which extends downwardly through the head B of the machine. Normally the rod 75 48 is in such position that the movable elements of the attachment are maintained in the positions shown by Fig. 4—that is, in the positions from which the movements heretofore described are made and to which 80 they are returned by the effort of the spring 46.

The lower end of the rod 48 is connected to an end of a bell-crank lever 49 pivoted at 50 to a frame member C of the machine. The other end of the lever is connected by a link 51 with an arm 52 of a shaft 53 journaled in a frame member of the machine. That shaft has extending therefrom a lug 54 positioned adjacent to the path of travel of the pattern-chain D and arranged to be swung by movement of certain lugs 55 on the chain for that purpose.

These lugs are spaced on the chain in such positions as to cause shifting of the movable elements of the attachment at the desired intervals and at the proper times with reference to the operation of the other pattern-controlling, actuating, and other instrumentalities of the machine. When and while one of these pattern-chain lugs moves and holds the lug 54 from its normal position, the rod 48 is raised and the movable elements of the attachment are actuated from their normal positions as hereinbefore explained. When a chain-lug passes from contact with the lug 54, the rod 48 and its actuating parts return to their normal positions under the influence of its weight and of the spring 46 and the movable elements of the attachment and the yarn-fingers return to their normal positions under the influence of that spring and of one of the springs 44.

Having thus described my invention, what I claim as new, and desire to secure by Letters Patent, is—

1. In a knitting-machine, the combination, with reversibly-shiftable fingers controlling the position of yarn passing to the needles, of mechanism for shifting said fingers, whereby reverse plating is effected, comprising a rock-shaft, an arm and eccentric part on said shaft, a pivotally-mounted member swingable by said eccentric part, springs holding said fingers against said arm and member, means controlled by said shaft whereby tension on yarn is altered simultaneously with the shifting of said fingers, and means whereby said shaft is rocked. 120 125

2. In a knitting-machine, the combination, 130

with reversibly-shiftable fingers controlling the position of yarn passing to the needles, of mechanism for simultaneously shifting said fingers and altering tension on yarn passing thereto, whereby reverse plating is effected, comprising a tension device for yarn passing to each of said fingers, a rock-shaft, an arm and eccentric part on said shaft, a pivotally-mounted member swingable by said eccentric part, springs holding said fingers against said arm and member, arms on said shaft arranged to alter tension of said tension devices on yarn passing to said fingers, and means whereby said shaft is rocked.

3. An attachment, for knitting-machines 15 for the simultaneous and reverse shifting of fingers controlling the position of yarn passing to the needles and alteration of tension on that yarn whereby reverse plating is effected, comprising yarn-tension devices, a 20 rock-shaft, a finger-shifting arm and an eccentric part on said shaft, a finger-shifting arm swingable by said eccentric part, and arms on said shaft cooperable with said tension devices to alter tension thereof on yarn 25 passing to the fingers.

In testimony whereof I affix my signature.

OWEN L. RIMEL.
